UNITED STATES PATENT OFFICE.

ROBERT A. JENNE, OF EUREKA, KANSAS.

HORSE-RELEASING DEVICE.

1,112,910.

Specification of Letters Patent.

Patented Oct. 6, 1914.

Application filed April 1, 1913. Serial No. 758,206.

To all whom it may concern:

Be it known that I, ROBERT A. JENNE, a citizen of the United States, residing at Eureka, in the county of Greenwood and 5 State of Kansas, have invented certain new and useful Improvements in Horse-Releasing Devices, of which the following is a specification, reference being had therein to the accompanying drawing.

10 This invention relates to horse releasing devices and has for its object the production of a simple and efficient horse releaser whereby the horse may be efficiently detached from the shafts of a vehicle in case 15 the horse should become frightened and run away.

Another object of this invention is the production of a simple and efficient means for attaching the harness to the shafts of a 20 vehicle in such a manner as to be quickly and efficiently released from the shafts.

With these and other objects in view, this invention consists of certain novel constructions, combinations and arrangements of 25 parts, as will be hereinafter fully described and claimed.

In the drawings:—Figure 1 is a top plan view of a pair of shafts showing the horse releasing mechanism attached thereto. Fig. 30 2 is a section taken on the line 2—2 of Fig. 1 looking in direction of the arrow. Fig. 3 is a detail perspective of one of the shaft engaging bands adapted to engage the back strap. Fig. 4 is aside elevation of one of 35 the clamping members adapted to engage a breeching strap. Fig. 5 is a central vertical sectional view through the clamping member adapted to engage the breeching strap. Fig. 6 is a sectional view taken on line 6—6 of Fig. 4. Fig. 7 is a detail perspective of one of the engaging links adapted to attach the breeching strap to the clamping member. Fig. 8 is a longitudinal section partly in elevation of the trace attaching 40 means adapted to be carried by the whiffle-tree. Fig. 9 is a section taken on line 9—9 of Fig. 8. Fig. 10 is a central horizontal section taken on line 10—10 of Fig. 8. Fig. 11 is a side elevation of the right-hand trace engaging clip which might be used in connection with the present invention.

50 By referring to the drawings, it will be seen that 1 designates the shafts which are provided with the usual cross tree member 2. The cross tree 3

pivots secured thereto by means of a pivot pin 4. A pair of clamping members 5 are secured to the shafts 1 and breeching strap engaging links 18 are secured to these straps 60 or clamps so as to be detached therefrom when the horse is released from the shafts.

The specific construction of this device will be disclosed in the following: A plurality of back band engaging members 7 are 65 also mounted upon the shaft 1 as illustrated in Fig. 1 and engage the heavy strap 8 which comes from the back band of any single harness on both sides to hold up the shaft.

70 The heavy strap 8 engages the member 7 which comprises a shaft engaging loop 9 which is circular in form so as to efficiently slip over the shafts 1. A clamping bridge portion 10 is formed upon the top of the body 75 portion 7 of the shaft engaging member and carries a locking pin 12 which locking pin is adapted to pass through the aperture 13 formed in the heavy strap 8. This pin 12 is normally held in its place by means of 80 a cotter pin or sealing ring 14 of any desired structure for preventing the pin 12 from becoming accidentally displaced from the heavy strap engaging member 7.

85 The body portion of the heavy strap engaging member 7 is provided with a downwardly extending loop portion 10 through which is adapted to pass the strap 8' from the bellyband of the harness to prevent the shaft from rising up when backing.

90 As is clearly illustrated in Figs. 4, 5 and 6, the breeching strap engaging member comprises a clamp 5 which is provided with parallel lips 15 and through these lips passes a locking bolt 16 for clamping the band 5 95 firmly around the shafts 1. The clamp 5 is provided also with an upwardly extending socket portion 17 in which fits the breeching strap engaging link 18. This socket portion 17 comprises a pair of spaced lips 19 and 20 100 which produce an opening 21 for facilitating the placing and removal of the link 18 into and out of the socket portion 17. It will be seen by means of the clamping bolt 16 that the clamp 5 may be firmly secured in 105 engagement with the shaft so as to prevent the same from becoming accidentally detached therefrom.

110 The breeching strap engaging link 18 comprises a substantially rectangular body and one side of the rectangular body portion is provided with a beveled surface 22 which

is so formed as to facilitate the placing of the link 18 in the socket 17. The opening between the spaced lips 19 and 20 is smaller than the thickness of the body of the link 18 so as to prevent the link 18 from being accidentally removed from the socket 17 under normal conditions. When the link 18 is thrown to the position as shown in dotted lines in Fig. 6, the beveled face 22 will be brought into engagement with the lip 20 and owing to the reduced thickness of the body portion will be allowed to move out from between the lips 19 and 20 and thereby allow the horse to be detached from the clamp 5. A downwardly projecting lug 23 is formed upon the link 18 and this downwardly projecting lug 23 is adapted to abut against the shoulder 24 formed upon the bottom of the lip 17, to prevent the link 18 from slipping too far in the socket 17 between the lips 19 and 20 when hitching up. It, of course, should be understood that the breeching strap 26 may be secured in any desired manner to the links 18 for accomplishing the desired purpose.

The whiffle-tree 3 carries a casing 27 at each end which contains the trace engaging portions for detaching the traces from the whiffle-tree. Each casing 27 is provided with a socket portion 28 which fits over the end of the whiffle-tree 3 and each casing 27 is provided with spaced lips 29 at its outer end between which lips is pivotally mounted the trace engaging knuckle 30. This trace engaging knuckle 30 comprises a wide body portion terminating in a reduced neck 31 which neck in turn terminates in a short finger 32 and a long finger 33. The trace is adapted to fit snugly over the neck 31 and under normal conditions will be held against removal from the neck by means of the long finger 33. This knuckle 30 is pivotally mounted between the lips 29 by means of the pivot bolt 34 and the under surface of the knuckle 30 rests upon the shoulder 35 formed upon the outer end of the casing 27.

The under portion of the knuckle 30 is provided with an aperture 36 which passes in a semi-circular form under the bridge portion 37 formed upon the under face of the knuckle 30. The hooked end 38 of the coil spring 39 is passed through this aperture 36 and fits over the bridge portion 37 and thereby constitutes an efficient means for securing the spring to the knuckle 30. The opposite end of the spring 39 is passed through the aperture 40 formed in the casing 27 and is securely held in engagement with the casing 37 by means of the hook 41 formed upon the end of the spring. It will be seen that the spring 39 will normally hold the knuckle 30 in the position as illustrated in full lines in Fig. 8, and at the same time will allow the knuckle 30 to be swung to the position as shown in dotted lines in Fig.

8, when unlocked by means of the locking lever 42. The locking lever 42 is pivotally mounted upon the pivot pin 43 in one side of the casing 27 and is normally held within the casing 27 by means of the coil spring 44 which coil spring fits over the bridge portion 45 which passes through the circular aperture 46. The spring 44 is provided with a hook portion 47 similar to the hook portion 38 of the spring 39 and thereby constitutes an efficient means for securing the spring to the locking lever 42. The opposite end of the spring 44 is secured to the casing 27 similar to the manner in which the spring 39 is secured thereto by means of the hook portion 48.

The locking lever 42 has an operating cable 49 secured to the inner end thereof, and has a knot 50 formed upon the end of the cable which knot fits in the socket 51 formed in the locking lever 42. This cable 49 passes through an aperture 52 formed in the casing 27 and this cable is likewise secured to the locking lever 42 of the opposite trace engaging means as illustrated in Fig. 90 and is in turn connected to an operating cable 53 which cable may pass to any desired position upon the vehicle.

From the foregoing description, it will be seen that when it is desired to release the horse from the vehicle, the cable 53 may be pulled, thereby swinging the locking lever 42 to the position shown in dotted lines in Fig. 8. This will allow the horse to pull forward upon the knuckle 30 and swing the same to the position shown in dotted lines, whereupon the trace will be slipped over the fingers 32 and 33 as the horse moves forward. At the same time the link 18 will be swung to the position shown in dotted lines in Fig. 6 and will thereby be removed from the clamp 5. As the horse continues in a forward direction, the heavy strap 8 and back band engaging member 7 will be slipped off the end of the shaft and the horse will then be free from the vehicle. It, of course, should be understood that the shafts may be held up by means of cables, ropes, or any other desired means, without departing from the spirit of the invention, 115 and, of course, any desired guiding means may be employed upon the vehicle. It is thought unnecessary to go into a detail description of this mechanism as the same is foreign subject-matter to the present invention.

The present construction of the attachment of the whiffle-tree to the trace is an important one especially owing to the manner in which the springs 39 and 44 are connected to the knuckle 30 and the locking lever 42. It should be understood that owing to the peculiar hooks 38 and 47 which are formed upon the springs 39 and 44, the same may be readily detached from the knuckle 130

30 and locking lever 42 by drawing the hooks 41 and 48 back from the casing 27 until the end of the hooks may be seen. Then swing the hooks 41 or 48 around so as 5 to pass through the apertures 40 where the same may be readily and easily removed from the bridge portions 37 and 45 whereupon new springs may be replaced therefor provided the springs 39 and 44 should be 10 come injured or otherwise unfit for use. The springs are replaced in the same manner as they are taken out with the exception that a small string or hook may be used to draw the hooks 41 or 48 through the aperture 40. 15 Of course, it should be understood that the present invention may be applied to a one or two-horse attachment for a vehicle without departing from the spirit of the invention.

20 Having thus described the invention, what is claimed as new, is:—

1. A trace connection for a whiffle-tree comprising a casing, a trace connecting knuckle pivotally secured upon said casing 25 and provided with a flat under surface, spring means for normally holding the same parallel with said casing, a locking lever pivotally secured upon said casing and pro-

vided with a flat outer end adapted to engage the under face of said knuckle for 30 locking the same against pivotal movement upon said casing, spring means for normally holding said locking lever parallel with said casing, and means engaging said locking lever for releasing said lever from 35 said trace engaging knuckle and allowing said trace engaging knuckle to swing to a forward position.

2. A device of the class described comprising a casing, a knuckle carried by said casing, said knuckle provided with a circular aperture upon the lower face thereof, a bridge portion straddling said aperture, a spring secured to said casing and provided with a hook fitting over said bridge portion 45 for detachably securing said spring to said knuckle, and locking means engaging said knuckle for normally holding said knuckle against pivotal movement upon said casing.

In testimony whereof I hereunto affix my 50 signature in presence of two witnesses.

ROBERT A. JENNE.
